Application October 27, 1932. Serial No. 639,776

7 Claims. (Cl. 41—1)

This invention relates to a method of producing decorative coatings by combined printing and blasting, and to apparatus by which such coating may be produced.

5 Since our invention is particularly adapted for the production of printed coatings on felt base floor coverings and other similar materials, it will be particularly described herein in connection with the manufacture of such goods. It is, however, not limited to the decoration of any particular type of object, but is capable of much wider application.

In the manufacture of printed floor coverings, the base sheet has been printed with designs by 15 means of sawed wooden blocks. Each of these blocks carries a raised area corresponding to one color portion of the design, and this raised portion is sawed along lines spaced approximately $\frac{1}{8}$ of an inch apart, so that the surface is divided 20 into narrow projections. A paint bucket with a roller which dips into the paint is passed under the print block after each printing operation and after the roller has contacted with the raised portions of the print block, a drop of the paint is 25 left suspended on each of the projections formed between the sawed cuts. In the case of line blocks, these drops will be in the form of long broad lines of paint, whereas in the case of pin blocks, the saw cuts are made crossing one another, so that the drops will be approximately 30 hemispherical, and about $\frac{1}{8}$ of an inch in diameter. When the material has been moved into printing position, and the paint pot moved away from the printing block, the block is dipped to 35 the surface of the sheet where the drops of paint are transferred from the bucket to the sheet. Since the drop of paint from each line or pin of the block is separately applied to the sheet, it frequently happens that the paint, after the 40 printing operation, is not in a smooth film, but is in the form of distinct lines or dots which do not always close in and flow together satisfactorily.

It is an object of the present invention to provide 45 a novel method of brushing out the paint which has been applied by printing in the usual manner, and thereby to insure perfect closing in. Another object of the invention is the production of novel design effects and irregular variations in design effects by means of a novel brushing out.

In the accompanying drawings we have illustrated 50 one apparatus embodying our invention, and certain modifications thereof which are well adapted to carry out the process of our invention.

tion. These are chosen as illustrative of the invention and for the purpose of assisting in the explanation of its operation and principle, and are not to be taken as in any sense limiting or restrictive.

In Fig. 1 is shown a side elevation partly in section and partly broken away, of a printing machine with which is associated a rotary air brushing device embodying our invention.

In Fig. 2 is a bottom plan view of one of the 65 rotary heads of the device shown in Fig. 1.

Fig. 3 is a plan view showing the arrangement of the rotary heads relative to the printed sheet.

Fig. 4 is an end elevation of another form of brushing-out mechanism embodying our invention; 70

Fig. 5 is a vertical section taken on line 5—5 of Fig. 4;

Fig. 6 is a bottom plan view, partly in section, of the device illustrated in Figs. 4 and 5, with 75 the slide jet removed;

Fig. 7 is a plan view of the bottom of this apparatus with the slide jet in position;

Fig. 8 is a plan view of another form of apparatus; and

Fig. 9 is a cross section taken on line 9—9 of Fig. 8.

The apparatus illustrated in Figs. 1 to 3 comprises a rotary brushing head, or series of brushing heads, associated with a printing machine 85 which may be of standard construction. The brushing heads 10 in this case are hollow casings having a narrow slit opening or openings or jets 11 on their lower faces. These jets 11 rotate very close to, but never touching the surface of 90 the paint or other print material which has been applied to the sheet or other object passed beneath them. Their number and arrangement, although shown as preferred, may be varied. They may, for example, be curved or at an angle 95 to the radius, and in some cases a parallel opening may be preferred to the form illustrated in Fig. 2.

The brushing heads 10 are supported close to the printed sheet by means of a framework 12, in 100 which they are rotatably supported, preferably through the air pipe 13, the hollow sleeve 14, and the connecting sleeve 15. The interior of the flanges on the sleeve 15 and the upper and lower edges of the flanges 15 and 16 are preferably machined and lubricated, so that the casing 10 and the sleeve 14 tend to maintain a substantially air-tight joint without necessity for stuffing boxes or other air-tight connections. A pulley 17 secured to the sleeve 14 serves to rotate the brush- 105 110

ing head, and is in this case driven in turn by means of the electric motor 18 and the driving belt 19.

In Fig. 3, the relation of the various heads to the width of the printed sheet is illustrated. As there shown, it is desirable that several heads should overlap slightly, so that no part of the sheet which is passed beneath them will escape the action of the brushing heads.

10 In Fig. 1 we have shown the brushing device broken away from the rest of the printing machine to indicate that the exact relation to the printing heads is not essential. To some extent, this relationship should depend upon the effect 15 which it is desired to produce. Thus, if the brushing is to be effected by means of a gentle air blast which will serve only to flatten out the ridges of the printed coating material sufficiently to insure their leveling and closing in, the brushing 20 device may follow immediately after the last printing head, or may be substituted for a printing head at an earlier position of the machine if it should be desired to brush out only a part of the coating which is to be applied. Ordinarily, 25 however, I prefer to position the device sufficiently beyond the last printing head so that there may be a substantial amount of slack between that printing head and the brushing device, so that the material may be drawn continuously beneath the 30 brushing heads, and the problem of arranging the heads to produce a uniform brushing effect upon sections successively brought beneath the heads may be avoided.

In the operation of the device as just described, 35 the sheet, e. g., of felt base material 20 is passed through the printing machine and the designs printed thereby by the successive printing heads, after which the sheet 20 is brought beneath the brushing heads 10. The latter are rotated by 40 means of the motor 18, and are supplied with the compressed air from the pipe 13. Under ordinary conditions, when a simple leveling effect is desired, the pressure supplied to these heads need not exceed two or three pounds above atmospheric. With higher pressures, various intermingling and veining or splashing effects may be obtained, as hereinafter described.

The effect which is to be obtained may also be varied by varying the speed of rotation of the brushing heads 10. For example, a slow rotation 50 may permit the paint or other coating material to flow ahead of the sheet jet produced by the slit opening 11, and may thus tend to intermingle adjacent portions of the coating material, and 55 to produce a blending or streaking out of the portions between areas to which different colors have been applied; whereas, with faster rotation, the blast from the jet may pass each portion of the coating material before it has had an opportunity 60 to flow very far from its original position, and the leveling effect may thus be produced with less tendency to blend or streak. In the case of marbleized patterns, the streaking of course is desirable, and in certain other designs, a blending and softening of the borders is highly 65 desirable.

In Figs. 5 to 7, we have illustrated another device embodying our invention. In this case, the brushing consists of a casing 21, to the 70 bottom of which is secured a stencil 22 and a sliding plate 23 having therein a narrow slot 24. The stencil and sliding plate assembly are held in position by means of clamping plates 25 and the stencil 22 is held against sliding by its engagement with the interior of the casing 21.

Sealing strips 26 of rubber, felt or other suitable material are preferably provided around the stencil openings so as to prevent escape of air between the slotted plate 23 and the stencil plate 22. Air is supplied to the casing 21 through the pipe 28, and the slotted plate 23 is slid back and forth across the stencil plate by means of a follower block 29, which engages in an endless reverse thread of a screw shaft 30. In some cases, the shaft 30 may be continuously driven so that the slotted plate 23 is continuously moved backward and forward over the stencil plate. Ordinarily, however, it will be better to hold the jet opening 24 away from the stencil plate during the movement of the sheet 20 beneath the brushing head, and this may be accomplished, for example, by driving the screw shaft 30 from the main drive shaft 31 of the printing machine. In the present instance I have shown the brushing device as replacing one of the printing heads on the machine, ordinarily the last, and have shown the drive for the screw shaft 30 as being taken from the cam shaft 32 through a gear box 33. Where the drive is to be intermittent, as described above, the gear box 33 advantageously includes a mutilated pinion, or a Geneva gear, or other intermittent drive mechanism, and the gear ratios are advantageously so adjust that the slide 23 will be moved across the stencil 22 and back again from the time when the sheet 20 is moved into position to the time when its next movement begins.

The device as illustrated in Figs. 4 to 7 is intended primarily for use with designs in which it is desired to avoid the brushing out of certain portions of the design. For example, where the blasting is to be carried on so as to effect a splashing or streaking of the colors to simulate a marble effect in a tile pattern, it will be desirable to avoid the crossing of the borders of each tile, and it may therefore be necessary to effect the blasting of adjacent tiles in separate operations. Or in case where marbleized tiles are to be separated by tiles of solid color, the blasting under conditions to produce streaking obviously should not be permitted to carry the streaking effect beyond the borders of the marbleized tile sections. This limiting of the blasting effect is controlled in the present case by means of a stencil block 22 and the sealing strips 26. When the slide 23 is moved beneath the stencil 22, its slit 24 passes across the openings of the stencil, and in so far as it coincides with those openings, a blast of air will be allowed to escape, but in so far as it coincides with the closed portions of the stencil, no blast will escape through the slit 24. Thus, as the slit passes from edge to edge across the stencil, the design areas corresponding to the openings in the stencil will be blasted, whereas the areas corresponding to the closed portions of the stencil will be protected from the air blast.

As already suggested above, it may be desirable to provide several successive heads of this type, each with a different stencil, so that different portions of the design may be blasted at different pressures or different speeds, or with different shape, size, or arrangement of the slit 24, so as to produce varied effects upon the different design areas.

The slit 24 may be curved or diagonal, instead of perpendicular to the line of movement as shown, and in such case the direction of streaking may be varied, and in some cases, also, it may be desirable to move the slide longitudinal-

ly of the sheet 20, rather than crosswise, so as to produce a longitudinal streaking. In some cases, also, it may be desirable to utilize several slots 24. Some of these may be positioned at angular or curved relation to others.

In Figs. 8 and 9, we show still another embodiment of the invention. In this case, the blast of air is delivered from a pipe 40 through rotating tubes 41 having slots 42. In the preferred embodiment, these slots are, as shown in Fig. 8, spiral, but it will be understood that they may be straight and parallel to the axis, or angular, or in any desired shape; or a plurality of short slots or drilled holes at different positions and/or 10 at different angles to the axis and radius may be used instead of slots as shown. The spiral form has a tendency to produce a more or less diagonal sweep of the air blast, whereas a straight slot parallel to the axis would produce a sweep longitudinal of the printed sheet. By mounting rotating tubes 41 longitudinally of the sheet, instead of crosswise, a perpendicular sweep blast of air may be obtained, or by decreasing the pitch of the spiral, the movement of the blast 20 may be made to take effect in a more nearly transverse direction. The choice of the particular direction and form of the slot 42 will thus be determined by the effect which it is desired to produce by brushing the printed coating with 25 the air blast.

Fig. 9 shows in cross-section an apparatus similar to Fig. 8, but in Fig. 9, guards 44 are positioned over the back of the rotating tubes 41 in order to avoid loss of air pressure from the backs of these tubes. By extending these guards 30 around so as to leave only a narrow slit, the effect may be further varied, and particularly in the case where holes instead of slits are used, the use of a narrow opening in the guard 44 will 40 give a series of puffs that will tend to produce an irregular, more or less sharp, intermixing of the adjacent colors.

Although the present invention may be useful for the treatment of any heavy coating,—that is, a coating of sufficient thickness to flow laterally, it will be found of particular advantage, where it is desired to produce designs with greater or less irregularities in repetition, as is the case where it is desired to simulate by mechanical printing designs which are formed by processes of nature, or by hand. Where a simple blending action is intended, we prefer to use cut-out printing, thus producing a sharply outlined design in which the color extends entirely 45 through the coating, and to subject this to a blast which is moved with sufficient rapidity so that the coating material must lag behind and cannot pile up and be carried ahead of the blast. On the other hand, where sharp, irregular effects 50 are desired, as in the case of imitations of marble, etc., it may be more desirable to print the simulation of the design by overlay printing, and in some cases, even with the use of colors which tend to flood. In this case, also, it will often be desirable 55 to use a slower moving blast, or one with greater force, so that there will be a tendency to move substantial amounts of the coating material of one color cut into the material of another color, and in some cases, instead of a moving blast, 60 it may be desirable to subject the coating suc-

cessively to intermittent blasts impinging thereon from different directions. Thus, the force of the blast may be regulated in amount, in direction, in continuity, and in movement or change of direction, and according to the regulation of the force in this manner, numerous different effects may be obtained as desired.

It is to be understood that the particular apparatus and methods described above are chosen for illustration and explanation of our invention, and that the invention is in no sense limited thereto, but on the contrary, that numerous other changes and modifications may be made within the scope, without departing from the spirit of our invention.

What we claim is:

1. In a block printing machine, the combination of means for printing a heavy coat of print material onto the surface of the object being printed, means for moving the object being printed into and away from printing position, and means for blasting with a compressed gas the surface of the print material while still fluid.

2. An apparatus for printing designs which comprises means for printing relatively heavy coats of print materials onto predetermined areas of an object being printed, means for moving the object, a movable air nozzle adapted to deliver a blast of air against the print material on said object and means for moving said nozzle so as to blast successively all portions of a predetermined area thereon.

3. An apparatus as defined in claim 2, in which the movable nozzle comprises a rotatable member having a long slot therein, through which a blast of air may be delivered against the print material on the printed object.

4. An apparatus as defined in claim 2, in which the movable nozzle comprises a movable member having a slot therein through which a blast of air may be delivered against the printed object, and the apparatus further comprises stencil associated with said movable member, so that when the latter is moved, the stencil will prevent the air from being delivered against predetermined areas on said object.

5. The method of surface decoration which comprises depositing liquid coloring materials upon adjacent areas of a surface to form a definite pattern and, while maintaining the approximate form of said pattern, blowing said coloring materials with an air blast so as to cause lateral flow thereof.

6. The method as defined in claim 5, in which the coloring material is applied in spaced drops from a sawed printing block, and the drops are made to flow laterally and coalesce into a continuous film by the blowing step.

7. The method as defined in claim 5, in which the coloring material is applied in a layer of sufficient thickness to permit it to flow out for a substantial distance from the area to which it is originally applied, and the blowing is directed against the coloring material at the borders of the pattern areas until it has been forced to interflow appreciably across said borders with the coloring material on adjacent pattern areas.

JAMES W. KEMMLER.
